UNITED STATES PATENT OFFICE.

OLIVER J. HOWE, OF BROCKTON, MASSACHUSETTS, ASSIGNOR TO MAWHINNEY LAST COMPANY, OF BROCKTON, MASSACHUSETTS, A CORPORATION OF MASSACHUSETTS.

SHOE-TREE.

Application filed July 21, 1921. Serial No. 436,419.

To all whom it may concern:

Be it known that I, OLIVER J. HOWE, a citizen of the United States, residing at Brockton, in the county of Plymouth and State of Massachusetts, have invented certain new and useful Improvements in Shoe-Trees, of which the following is a specification.

This invention relates to improvements in shoe trees. More especially it relates to followers or forms adapted for use by makers, merchants and consumers, during manufacture, display as merchandise, and between periods of wear. It has among its objects the provision of a simple and inexpensive yet good construction of shoe tree whose split fore part spreads upon the swinging of the heel part into the shoe, and contracts when the heel part is withdrawn, combined with means whereby these parts may fit different lengths of shoes.

The invention provides a fore part split lengthwise into sections hinged together near the toe, and connected operably together and to the heel, near their rear ends, by a T-joint, comprising a tubular pivot crossing the plane of cleavage, and journaled in the wood. This tube has a short helical slot in each end portion, into which a pin projects from the wood. Upon the pivot being rotated these slots act as cams to move the pins along the axis of the pivot and so to spread the sections, or contract them. This rotation occurs automatically whenever the heel ball, on the leg of the T, is swung into or out of the shoe.

One embodiment of the invention is illustrated in the accompanying drawings. It is intended that the patent shall cover, by suitable expression in the appended claims, whatever features of patentable novelty exist in the invention disclosed.

In the drawings:

Fig. 1 is a plan, viewed from the bottom of a shoe tree, constructed in accordance with the invention;

Fig. 2 is an elevation, in section on line 2—2 of Fig. 1;

Fig. 3 is a plan of a portion of the tree, in section on line 3—3 of Fig. 2; and

Fig. 4 is a plan of a detail.

Referring to the drawings, the fore part comprises the separated sections 10 and 12 hinged together near their forward ends by a transverse cord 14 held in a hole in

each section by a pin 16. The cord bends as the sections may move to and from parallelism. Near the rear end of each section a cylindrical hole 18 extends into the section from the medial cleft 20 at right angles to that cleft, and houses one end of a tube 22 which extends crossways from one fore part section to the other with loose fit, exaggerated in the drawings for clearness. These holes are merely bored into each section perpendicularly. The tube may be rolled up from a piece of flat metal, shown so in Fig. 4, in which slots 24 and 26 have been punched at an inclination to each other so that, when the sheet is bent into tubular form, these slots will converge toward a plane at right angles to the axis of the shell, or this may be ordinary tubing with saw cuts. Holes 27 may also be stamped out of the flat plate, at predetermined points on the same center line so that when the plate is rolled into cylindrical form, these holes, will be opposite each other in the shell. A pin 28, which may be an ordinary wire nail, is set in each fore part and passes through one of the slots into the hollow of the tube, substantially perpendicular to its axis of rotation. This arrangement of the pins and slots causes the sections to move together or apart, as the tube is rotated, the sides of the slots acting as cam faces on the pins.

The connection to the heel part 34 comprises an extensible rod 30 threaded transversely through the holes 27 of the tube at its middle at right angles to the tube's axis of rotation, the end of the rod terminating flush with the outside of the tube. The other end of this rod is a plunger sliding within a tube 32 to which the heel part 34 is secured. Within the tube 32 is a spring 36 acting to push out the end of the plunger 30, and thus tending to keep the heel part extended from the fore part, but limited in its effect by a pin 38 set in the side of the plunger within a slot 40 in the tube 32. Complete separation of the latter from the plunger is prevented by the pin meeting the end of the slot. Thus the fore sections and the heel are connected by a sort of T-joint, one part being on each limb of the T. The head of the T keeps the sections side by side, at the same time permitting their separation and approach; the leg is a handle for turning the head on the line of the head as an axis; and the turning in

either direction varies the distance apart of the fore sections, and occurs with each swing of the heel into and out of the shoe.

In operation the heel part being raised 5 relative to the forepart, and the fore part thus contracted, the fore part is to be pushed into the shoe as far as it will go. The heel part is then swung downward into the heel of the shoe, the spring 36 being compressed 10 if necessary to shorten the overall length and permit the heel part 34 to get in. As the heel part swings downward into the shoe the cam action of the helical slots in the tubular pivot spreads the sections of the fore 15 part until these sections press firmly outward on the interior of the shoe, keeping the vamp filled out as though by the foot of the wearer. In case the spread of the fore parts, which would be thus attained, is 20 greater than the width to which the shoe can comfortably stretch, the fore part of the tree as a whole may slip rearward within the shoe, the spring 36 compressing an additional amount to allow this retraction of 25 the fore part. This feature prevents any excessive pressure against the walls of the shoe by the fore part and eliminates the danger of splitting the leather, which has hitherto been a weakness in this particular 30 form of tree, where the spreading has been positive in a sidewise direction with no provision for lengthwise displacement to allow the form to adjust itself to the shoe.

I claim:

35 1. A three-block shoe tree comprising two fore blocks which together constitute a forepart, separated by a longitudinal cleft and hinged together at the toe; the third block, constituting the heel part and located at a 40 distance from the forepart; an extensible-leg T-shaped junction member for the three blocks; and a pin driven through the wood of each fore block into the head of the T; the leg of the T rigidly attached to the heel 45 and running into the cleft of the forepart to the head of the T; and the head of the T being set loosely in socket holes sunk transversely in the fore blocks and having cam slots in which the pins engage, holding the 50 whole together with the T capable of limited swing around its said head.

2. A shoe tree comprising in combination 55 a forepart divided longitudinally into sections, hinged together at the toe; a heel part at a distance therefrom; and a T-junc-

tion member for them all, the head of the T being tubular and extending transversely and rotatable into sockets in the forepart sections with cam slots for spreading them, and the leg of the T being extensible; there 6 being a fixed element on each section engaging a slot of the T.

3. A shoe tree comprising in combination a forepart divided longitudinally into sections, hinged together at the toe; a heel part 65 at a distance therefrom; and a T-junction member for them all, the head of the T being tubular and extending transversely and rotatably into sockets in the forepart sections with cam slots for spreading them; a pin in 70 each section engaging said slots; the leg of the T being extensible and comprising a plunger slidable in a sleeve secured to said heel part; there being a spring between said plunger and said sleeve whereby the tree 75 yields with elastic pressure as the heel is swung into a shoe.

4. A shoe tree comprising a forepart having sections hinged at the toe and movably connected at their rear by a cylindrical shell 80 extending transversely to their plane of separation having inclined slots in its wall; pins, adapted to coact with the shell, driven from the outside through the sections into 85 said slots, there being a pin in each section and a slot for each pin; a rod threaded fixedly through said shell at right angles to its axis and extending rearward; a heel part secured on said rod and swinging therewith to rotate said shell; the said rotative movement being transmuted by said slots and pins into swinging movement of the forepart sections about their hinge.

5. A shoe tree comprising a forepart in two wooden block sections hinged at the toe, 90 each having a hole near its rear bored outward from the cleft between the two and constituting a socket; a heel part comprising a portion extending into said cleft having at its end a cylindrical shell rotatable 100 within said sockets and having a pair of cam slots in its wall; and a pin in each block section projecting into one of said slots and coacting therewith to swing the forepart sections about their hinge as the heel part 105 is swung about the axis of said shell.

Signed at Brockton, Massachusetts, this eighth day of July, 1922.

OLIVER J. HOWE.
